UNITED STATES PATENT OFFICE.

GEORGE H. BARBOUR, OF PITTSBURGH, PENNSYLVANIA.

METHOD OF BENDING FLANGED SHAPES.

1,182,070.

Specification of Letters Patent.

Patented May 9, 1916.

Continuation of application Serial No. 547,418, filed March 5, 1910. This application filed May 16, 1913.
Serial No. 768,055.

To all whom it may concern:

Be it known that I, GEORGE H. BARBOUR, a citizen of the United States, and a resident of Pittsburgh, in the county of Allegheny and State of Pennsylvania, have invented a new and useful Improvement in Methods of Bending Flanged Shapes, of which the following is a full, clear, and exact description, reference being had to the accompanying drawings, forming part of this specification, in which—

Figure 1 is a front view of a portion of a three-high mill showing one method of bending flanged sections from a blank. Fig. 2 is a similar view for bending flanged sections from a differently shaped blank. Fig. 3 is a similar view for bending a differently shaped section from the blank shown in Fig. 1. Fig. 4 is a similar view for bending a section similar to that shown in Fig. 3 from a blank similar to that shown in Fig. 2. Fig. 5 is a similar view of an apparatus for bending still a differently shaped section from a blank similar to that shown in Fig. 1. Fig. 6 is a similar view of an apparatus for bending still another form of section from a blank. Figs. 7, 8, 9, 10 and 11 are sectional views of a plurality of blanks and sections formed therefrom by my method. My invention relates to an improved method for roll-bending flanged sections having a web and a plurality of flanges, and is designed to provide a cheap and efficient method of bending the flanges or a portion thereof with relation to the web.

The precise nature of my invention will be best understood by reference to the accompanying drawings, which will now be described, it being premised, however, that various changes may be made in the details of construction of the apparatus and general arrangement of the parts, as well as the various steps of the method, without departing from the spirit and scope of my invention, as defined in the appended claims.

In Figs. 1 to 6, A, B, and C designate the rolls of a three-high mill, between which is formed a plurality of passes for bending the various sections from the blank.

In Fig. 1, I have shown an apparatus for bending a section such as is shown at a^5 , which consists of a web and a plurality of flanges at each end of the web, a portion of each of the flanges being at substantially right angles to the web, while the extremi-

ties thereof are at substantially right angles to the other portions of the flanges and substantially parallel with the web. In forming this section, I take a blank, as indicated at a , and run it through a pass a^2 in which both sides of the web are engaged by the rolls, while the web extends at an angle of approximately 45 degrees to the axes of the rolls, and in which pass, I bend a portion of two of the flanges at an angle of approximately 90 degrees to the web, and maintain the other two flanges at approximately an angle of 45 degrees to the web. I then run the section through a second pass, as indicated at a^3 , and maintain the web at an angle of approximately 45 degrees to the axes of the rolls, and bend a portion of each of these flanges at an angle of 90 degrees to the web, without changing the angular relation of the other portions thereof. After the blank has been run through this last mentioned pass, a portion of each of the flanges will extend at substantially right angles to the web, while the outer extremities thereof will extend at an angle of substantially 45 degrees to the other portions of the flanges and the web. I then run the blank through a pass, such as indicated at a^4 , and bend the extremities of one of the flanges at each end of the web at about right angles to the other portion of each flange and parallel with the web. The blank is then run through another pass, as indicated at a^5 , to bend the extremities of the other two flanges to form a section having a web and a plurality of flanges at each end of the web, the outer extremities of the flanges being substantially parallel with the web and at about right angles to the other portions of the flanges.

In Fig. 2, I have shown another form of apparatus for rolling the same section from a section or blank such as shown at m^2 and n^2 in Figs. 5 and 6, respectively. In this case, I bend the outer extremities of two of the flanges at an angle of about 45 degrees without disturbing that portion of the flanges adjacent to the web as indicated at b^2 . The blank is then run through a pass, as indicated at b^3 to shape the blank similar to the blank shown at a^3 in Fig. 1. This blank is then run through passes b^4 and b^5 , which are similar to passes a^4 and a^5 of Fig. 1.

In Figs. 3 and 4, I have shown rolls for

forming a section similar to those shown in Fig. 1, with the exception that in these sections the outer extremities of the flanges extend toward each other instead of away from each other. In Fig. 3, I take a blank, such as shown at c , and run it through the pass c^1 to bend the outer extremities of a flange at each end of the web. The blank is then run through pass c^2 to bend the outer extremities of the other two flanges, so that the flanges on each end of the blank have a portion extending at an angle of substantially 45 degrees with relation to the web, and another portion extending at an angle of substantially 90 degrees to the web. The blank is then successively run through passes c^3 and c^4 to bend the outer extremities of the flanges at substantially right angles to the other portions thereof. It is then run through passes c^5 and c^6 to bend the flanges 45 degrees with relation to the web, so that a portion of each flange extends at substantially right angles to the web, and another portion substantially parallel therewith.

In Fig. 4, I have shown an apparatus for bending a similar section to that shown at c^6 in Fig. 3 from an I-beam shown at c^{11} . In this method, I run the section through the pass c^{12} to bend the outer extremities of two of the flanges at an angle of about 45 degrees, with relation to the web and flanges, and then run the section through the pass c^{13} to bend the extremities of the other flanges in a similar manner. The blank is then run through passes c^{14} and c^{15} to bend the outer extremities of the flanges another 45 degrees, so that the outer extremities of the flanges on opposite ends of the blank extend toward each other substantially parallel with the web and at an angle of about 90 degrees to the flanges.

In Figs. 5 and 6, I have shown other forms of apparatus for forming I-beam sections m^2 and n^2 from a blank such as shown at m , m , by running it through passes m^1 and m^2 , or through passes n^1 and n^2 .

In Fig. 7 I have shown at E a blank similar to that shown at a in Fig. 1; and e^1 e^2 , e^3 , e^4 , e^5 , e^6 , e^7 , e^8 , e^9 , e^{10} , e^{11} , e^{12} , e^{13} , e^{14} , e^{15} , e^{16} , e^{17} , e^{18} , e^{19} , e^{20} , e^{21} , e^{22} , e^{23} , e^{24} , e^{25} , e^{26} , e^{27} , e^{28} , e^{29} , e^{30} , e^{31} , e^{32} , e^{33} , e^{34} , e^{35} and e^{36} designate a number of other sections which may be formed from said blank, which differ from those shown in the various roll passes shown in Figs. 1 to 6.

In Fig. 8, F designates a blank similar to that shown in Fig. 7, with the exception that it only has three flanges. These three flanges may be bent in a manner similar to three of the flanges in the section shown in Figs. 1 to 6, and f^1 , f^2 , f^3 , f^4 , f^5 , f^6 , f^7 , f^8 , f^9 , f^{10} , f^{11} , f^{12} , f^{13} , f^{14} , f^{15} , f^{16} , f^{17} , f^{18} , f^{19} , f^{20} , f^{21} , f^{22} , f^{23} , and f^{24} designate a few other sections which can be formed from the blank F.

In Figs. 9, 10 and 11 I have shown at G,

H and J, respectively, other blanks, each of which is provided with a web and two flanges. The two flanges of each of these blanks may be bent to form sections such as shown at g^1 , g^2 , g^3 , g^4 , g^5 , g^6 , g^7 , g^8 , g^9 , g^{10} , g^{11} , g^{12} , g^{13} , g^{14} , g^{15} , g^{16} , g^{17} , g^{18} , h^1 , h^2 , h^3 , h^4 , h^5 , h^6 , h^7 , h^8 , h^9 , h^{10} , h^{11} , h^{12} , and j^1 , j^2 , j^3 , j^4 , j^5 , j^6 , j^7 , j^8 , j^9 , j^{10} , j^{11} , j^{12} , j^{13} , j^{14} , j^{15} , j^{16} and j^{17} , respectively.

In the description of Figs. 1 to 6, inclusive, I have described all of the steps for forming sections such as shown at a^5 , b^5 , c^6 , c^{15} , m^2 and n^2 , but I desire it to be understood that the sections formed by any of the intermediate passes are adaptable for use for various purposes. It will also be understood by those familiar with the art, that various other sections than those shown in the drawings may be formed by this method.

In the above mentioned figures, I have shown a plurality of sections which may be formed from the various blanks by means of the various steps set forth in the method of roll bending sections, while running the sections through roll passes in which the webs are maintained at an angle of approximately 45 degrees to the axes of the rolls, so that the rolls will engage both sides of the web and both sides of the flanges which are being bent.

The advantages of my invention result from the provision of a method for bending sections having a web and a plurality of flanges at each end of the web, the flanges having one portion at an angle to another portion thereof. Further, from the provision of rolls which are arranged to engage both sides of the web while bending the flanges to form an I-beam from a rolled section, or a section having a web and a plurality of flanges at each end thereof, each having two portions at an angle to each other, and thereby avoid distorting the section.

This application is a continuation of my application Serial No. 547,418, filed March 5, 1910.

I claim:

1. The method of shaping a section having a web and at least two flanges extending from the web between rotary bending means, consisting in moving the blank in a longitudinal direction between the bending means and engaging both sides of one flange and both sides of the web and bending said flange at a different angle with relation to the web, while engaging at least one portion of one face of the other flange, and maintaining the web at an angle to the line of engaging pressure and at an angle to a line perpendicular to the line of the engaging pressure, then moving the blank between the bending means a second time and engaging both sides of the second flange and both sides of the web and bending the sec-

ond flange with relation to the web, while engaging at least one portion of one face of the first flange, and maintaining the web at an angle to the line of the engaging pressure and at an angle to a line perpendicular to the line of the bending means, substantially as described.

2. The method of shaping between rotary bending means a section having a plurality of flanges extending from a web, consisting in moving the blank between the bending means and engaging both sides of two of the flanges and both sides of the web and bending at least one portion of each of said flanges at a different angle with relation to the other portion thereof, and at the same time engaging at least one portion of one face of another flange, and maintaining the web at an angle to the line of the engaging pressure and at an angle to a line perpendicular to the line of the engaging pressure, substantially as described.

3. The method of shaping a section having a plurality of flanges extending from each end of the web between rotary bending means, consisting in moving the blank between the bending means in a longitudinal direction and engaging both sides of a pair of alternate flanges and both sides of the web and bending said flanges at a different angle with relation to the web, while maintaining the web and another pair of flanges at an angle to the line of the engaging pressure and at an angle to a line perpendicular to the line of the bending means, substantially as described.

4. The method of shaping a section having a plurality of flanges extending from each end of the web between rotary bending means, consisting in moving the blank between the bending means in a longitudinal direction and engaging both sides of a pair of alternate flanges and both sides of the web and bending said flanges at a different angle with relation to the web, while maintaining the web and another pair of flanges at an angle to the line of the engaging pressure and at an angle to a line perpendicular to the line of the engaging pressure, and then moving the blank a second time in a longitudinal direction between the bending means and engaging both sides of each of the other flanges and both sides of the web, and bending the last mentioned flanges at a different angle with relation to the web and maintaining the web at an angle to the line of the engaging pressure and at an angle to a line perpendicular to the line of the engaging pressure, substantially as described.

5. The method of shaping between rotary bending means a section having a web and at least two flanges extending from the web, consisting in moving the blank between the bending means and engaging both sides

of one of the flanges and both sides of the web and bending at least one portion of said flange at a different angle with relation to another portion thereof and at the same time engaging at least one portion of one face of the other flange, and maintaining at least one portion of each flange in planes parallel to each other and maintaining the web at an angle to the line of the engaging pressure and at an angle to a line perpendicular to the line of the engaging pressure, substantially as described.

6. The method of shaping a section having a web and two flanges extending from each end of the web between rotary bending means, consisting in moving the blank in a longitudinal direction between the bending means and engaging both sides of a pair of alternate flanges and both sides of the web and bending the extremity of each of said flanges at a different angle with relation to another portion of each of said flanges, and at the same time engaging at least one portion of each face of the other pair of flanges and maintaining at least a portion of each of the four flanges in parallel planes and maintaining the web at an angle to the line of the engaging pressure and at an angle to a line perpendicular to the line of the engaging pressure during the bending operation, substantially as described.

7. The method of shaping a section having a web and two flanges extending from the web between rotary bending means, consisting in moving the blank between the bending means and engaging both sides of one flange and both sides of the web and bending at least one portion of said flange with relation to the web and at the same time engaging at least one portion of one face of the other flange, and during said bending maintaining at least one portion of each flange in planes parallel to each other and maintaining the web at an angle to the line of the engaging pressure and at an angle to a line perpendicular to the line of the engaging pressure, then moving the blank in a longitudinal direction a second time between the bending means and engaging both sides of the other flange and both sides of the web and bending at least one portion of the second flange at a different angle with relation to the web and during said bending action engaging at least one portion of one face of the first flange and maintaining at least one portion of each flange in planes parallel to each other, and during said bending action maintaining the web at an angle to the line of the engaging pressure and at an angle to a line perpendicular to the line of the engaging pressure, substantially as described.

8. The method of shaping a section having a web and a plurality of flanges at each end of the web between rotary bending

means, consisting in moving the blank between the bending means in a longitudinal direction and engaging both sides of a pair of alternate flanges and both sides of the 5 web and bending at least one portion of each of said flanges at a different angle with relation to the web, and at the same time engaging at least one portion of one face of each of the second pair of alternate flanges 10 and maintaining at least a portion of each of the four flanges in planes parallel to each other and maintaining the web at an angle to the line of the engaging pressure and at an angle to a line perpendicular to 15 the line of the engaging pressure, then moving the blank a second time between the bending means and engaging both sides of each of the unbent flanges and both sides of the web, and bending at least one portion of 20 each of said flanges at a different angle with relation to the other portions of said flanges and also engaging at least one portion of one face of each of the bent flanges and maintaining at least one portion of each of the 25 four flanges in planes parallel to each other while maintaining the web at an angle to a line perpendicular to the line of the engaging pressure, substantially as described.

9. The method of shaping a section having a web and a plurality of flanges extending from the web between rotary bending means, consisting in moving the blank in a longitudinal direction between the bending means and engaging both sides of one flange 30 and both sides of the web and bending one portion of said flange at a different angle with relation to another portion, and at the same time engaging at least one portion of one face of another flange, and during such 35 bending maintaining at least one portion of the second flange at an angle to a portion of the first flange and maintaining the web at an angle to the line of the engaging pressure and at an angle to a line perpendicular to 40 the line of the engaging pressure, then moving the blank between the bending means a second time and engaging both sides of the web and both sides of the second flange and bending a portion of the second flange at a 45 different angle with relation to another portion thereof, and during said bending action engaging at least one portion of one face of the bent flange and maintaining at least one portion of the first flange at an angle to at 50 least one portion of the second flange, and maintaining the web at an angle to the line of the engaging pressure and at an angle to a line perpendicular to the line of the engaging pressure, substantially as described.

55 10. The method of shaping a section having a web and a pair of oppositely extending

flanges at each end of the web between rotary bending means, consisting in moving the blank in a longitudinal direction between the bending means and engaging both sides 65 of a pair of alternate flanges and both sides of the web and bending at least a portion of each of said flanges at a different angle with relation to the web, and during such bending action engaging at least one portion of one face of each of the other flanges and maintaining at least one portion of each of the flanges at one end of the web in the same plane and at least a portion of each of the pair of flanges at the other end of the web 70 in another plane, and also maintaining the web at an angle to the line of the engaging pressure and at an angle to a line perpendicular to the line of the engaging pressure, then moving the blank between the bending 75 means a second time and engaging both sides of each of the second pair of alternate flanges and both sides of the web and bending at least one portion of each of the other alternate flanges at a different angle with 80 relation to the web and during such bending action engaging at least one portion of one face of each of the first bent flanges and maintaining at least one portion of each of the flanges at one end of the web in the same 85 plane and at least one portion of each of the flanges at the other end of the web in another plane, and also maintaining the web at an angle to the line of the engaging pressure and at an angle to a line perpendicular to the line of the engaging pressure during 90 the bending action, substantially as described.

11. The method of shaping a section having a web and two flanges extending from each end of the web between rotary bending means, consisting in moving the blank between the bending means and engaging both sides of two of the flanges and both sides of the web and bending at least one portion of each of said flanges at a different angle with 100 relation to the web while engaging at least one portion of one face of each of the other two flanges and maintaining at least one portion of each of the four flanges in a different plane and maintaining the web at an angle to the line of the engaging pressure and at an angle to a line perpendicular to the line of the engaging pressure, substantially as described.

In testimony whereof I have hereunto set my hand.

GEORGE H. BARBOUR.
